[57] CLAIM

The ornamental design for the lint remover handle, as shown and described.

DESCRIPTION

FIG. 1 is a perspective view of the lint remover handle of my new design, shown in an operational environment;

FIG. 2 is a side elevational view thereof, the opposite side being identical thereto;

FIG. 3 is a front elevational view thereof, the rear being identical thereto;

FIG. 4 is a right end view thereof; and,

FIG. 5 is a left end view thereof.

The broken line structure that is shown in FIGS. 1-4 is for illustrative purposes only and forms no part of the claimed design.
